UNITED STATES PATENT OFFICE.

JOHN DAVID HAY, OF CHICAGO, ILLINOIS, ASSIGNOR OF ONE-HALF TO WILLIAM R. DONALDSON AND ONE-FOURTH TO GEORGE W. MARBLE, BOTH OF CHICAGO, ILLINOIS.

EXPLOSIVE-ENGINE.

No. 880,024.

Specification of Letters Patent.

Patented Feb. 25, 1908.

Application filed October 13, 1906. Serial No. 338,752.

To all whom it may concern:

Be it known that I, JOHN D. HAY, a citizen of the United States, and a resident of the city of Chicago, in the county of Cook and 5 State of Illinois, have invented certain new and useful Improvements in Explosive-Engines; and I do hereby declare that the following is a full, clear, and exact description of the same, reference being had to the accompanying drawings, and to the letters of 10 reference marked thereon, which form a part of this specification.

This invention relates to an improvement in explosive engines and is shown embodied 15 as a two cycle or two stroke engine.

Heretofore in engines of the class described, the explosive mixture has usually been delivered into the inner end of the cylinder through ports controlled by the piston, and 20 owing in part to the frequency of the explosions there is doubtless a somewhat greater tendency to heat the piston than in engines of four cycle or four stroke type. While adequate provision can be made for cooling the 25 cylinder either by means of a water jacket or by means of radiating pins or ribs, it is much more difficult to cool the piston. It is also of the utmost importance in engines of the class described to so regulate the charge 30 of the explosive mixture as to enable the speed and general operation of the engine to be adequately controlled.

The object of this invention is to provide means for cooling the piston by admitting 35 therethrough a cooling fluid or vapor conveniently the explosive mixture.

It is a further object of the invention to afford in the inner end of the piston a cooling chamber of large area in which a cooling fluid 40 is permitted to expand and to afford in connection with the improved piston means for regulating and automatically controlling the delivery of the charge into the cylinder.

The invention consists of matters herein- 45 after described and more fully pointed out and defined in the appended claims.

In the drawings: Figure 1 is a top plan view of a device embodying my invention. Fig. 2 is a central vertical section of an engine embodying my invention. Fig. 3 is an 50 enlarged section of the piston taken through

the cooling chamber. Fig. 4 is a fragmentary section similar to Fig. 2 and showing a slightly modified construction of the piston and cylinder. Fig. 5 is an enlarged detail of 55 the controlling valve.

As shown in the drawings: A indicates the crank case of an explosive engine which for convenience is shown as affording a preliminary compression chamber for the explosive mixture before delivery into the cylinder.

B indicates the cylinder secured thereon as is usual and it is provided with an exhaust port b adapted to be opened or uncovered by 65 the piston C when at the limit of the power stroke. An inlet port b' is oppositely disposed from said exhaust port and somewhat below the same and of less area and is adapted to be uncovered by the piston shortly after 70 the exhaust port is opened or partly opened.

Connected in the crank case is an inlet pipe D for the explosive mixture which is connected to a suitable carbureter or mixing valve E, of any suitable type and in any 75 suitable manner and is provided with an inwardly opening check valve d to hold the compression of the mixture in the crank case during the power stroke of the piston as shown in Fig. 2.

The piston C as shown is connected with the crank shaft F, by the connecting rod f, as is usual and in the upper end of the piston is provided a chamber C' as nearly as possible coincident in area on its upper side with the 85 area of said chamber. The end walls or head of the piston is made relatively thin. Said chamber communicates with the interior of the crank case through a port c of relatively large size, and discharges through 90 the opposite wall of the piston, and the cylinder by means of a port c' of still larger size.

In the wall of the cylinder and positioned to register with the port c' when the piston is at the end of its power stroke is a port b², 95 which communicates with a cored passage b³, which extends upwardly to and communicates with the inlet port of the cylinder. Seated in said passage and controlling the flow of the explosive mixture therethrough is 100 a regulating valve comprising as shown a cage G, fitted in a suitable recess opening in

said inlet passage b^3 and which as shown is provided with a cylindric bore and is longitudinally slotted in its periphery, said slots g , opening therethrough into the said inlet 5 passage. Rotatively engaged in said cage and fitting closely therein is the valve closure G' , which corresponds in construction with said cage, and is likewise provided in its periphery with slots g^2 adapted to register 10 with the slots g in the cage. Said closure is also provided in its head with apertures g^3 , to permit inlet pressure to be balanced in 15 said valve. A stem g^4 , extends outwardly through the head of said cage, and upon the same is rigidly engaged an actuating arm or 20 lever H , adapted to be connected with any suitable governor which inasmuch as it may be any of the usual centrifugal governors is not shown. The surface of the piston head 25 as shown affords an upwardly directed and slightly inclined shoulder C^2 curved outwardly at its base which serves to deflect the inflowing mixture upwardly to the head of the cylinder to aid in expelling the burned 30 gases. From the upper surface of said shoulder or deflector the surface of said piston is slightly concave as shown in Figs. 2 and 4 inclining outwardly and downwardly towards the exhaust port thus insuring the opening of the exhaust port slightly before the inlet port opens.

If desired the cylinder may be constructed as hereinbefore described with the exception that a passage b^5 is cored in the cylinder extending from the crank case upwardly as 35 shown in Fig. 4 and opening through a suitable port c^5 to the piston which is also provided with a port c^6 to register therewith thus enabling the piston to act as a double closure 40 to prevent any of the explosive mixture passing into the cylinder until both ports in the piston are in register.

The operation is as follows: The engine is similar to the usual two cycle or two stroke 45 explosive engine with the exception that the inflowing explosive mixture must pass through the head of the piston, expanding therein at the moment the ports come in register. The relatively large chamber in 50 said piston enables the head to be cooled by contact with the inflowing gases. Inasmuch as the exhaust port is opened before the flow of the explosive mixture begins, the pressure in the cylinder is about normal 55 atmospheric pressure; therefore the explosive mixture in the crank case normally under considerable pressure instantly expands in said chamber thus acting not only to cool the head of the piston by contact but also by the expansion of said gas in said 60 chamber. The amount of gas permitted to flow into the cylinder is of course regulated by the controlling valve, actuated by any suitable or well known type of centrifugal or

other governor. The closure of the controlling valve rotates to partly close the same when the speed of the engine is above normal or that for which the governor is set and opens or partly opens the same when the speed falls below normal. In this way the amount of the charge delivered into the cylinder is at all times regulated, economizing in fuel and insuring that the explosive mixture is delivered into the cylinder in just the right quantity to insure the most effective result.

I do not purpose limiting this application for patent otherwise than necessitated by the prior art as many details of construction and operation may be varied without departing from the principle of my invention.

I claim as my invention:

1. In a device of the class described the combination with a crank case and cylinder secured thereto having an inlet port of a passage cored in the wall of the cylinder opening directly into the crank case at one end and opening through the side of the cylinder, an exhaust port opening from the cylinder above said passage, a piston in said cylinder having a chamber in the head thereof, passages leading downwardly therefrom through the wall of the piston and opening outwardly, one of said passages adapted to register with the end of the passage in the cylinder wall and a passage adapted to communicate with the other passage in the piston at the lowest limit of movement of the piston and also communicating with the inlet port for the cylinder.

2. In a device of the class described the combination with a crank case and cylinder of a piston therein having a passage opening through one side thereof and extending upwardly through the side wall of the same beneath the piston head and extending downwardly through the wall of the piston on the opposite side thereof, a passage in the wall of the cylinder adapted at one end to communicate with one end of the passage in the piston and at its opposite end opening directly into the crank case and a pipe opening into the cylinder at one end to communicate with the other end of said passage in the piston and at its opposite end opening into the cylinder above the piston at its lowest limit of movement.

3. In a device of the class described the combination with a crank case and cylinder of a piston in the cylinder having oppositely disposed passages in its side walls opening through the piston at their lower extremities and communicating with a chamber in the piston head, a passage in the wall of the cylinder having one end opening into the cylinder and adapted to communicate with one of said passages therein and at its opposite end opening into the crank case and not controlled by the piston, a passage opening at

one end through the cylinder adapted to communicate with the other passage in the piston and affording communication with the cylinder above the piston at the limit of its power stroke and a controlling valve in said last named passage.

In testimony whereof I have hereunto sub-

scribed my name in the presence of two subscribing witnesses.

JOHN DAVID HAY.
